UNITED STATES PATENT OFFICE.

ERNEST F. HOWE, OF CLINTON, MASSACHUSETTS.

SUBMARINE LIFE-BOAT.

1,259,627.

Specification of Letters Patent. Patented Mar. 19, 1918.

Application filed January 6, 1917. Serial No. 141,017.

To all whom it may concern:

Be it known that I, ERNEST P. HOWE, a citizen of the United States, residing at Clinton, in the county of Worcester and State of Massachusetts, have invented a new and useful Submarine Life-Boat, of which the following is a specification.

This invention relates to a lifeboat particularly adapted for use in association with a submarine boat.

It is desirable that such a lifeboat shall be able to both leave and return to the submarine while the latter is submerged. Accordingly, it is one object of my invention to provide mechanism by which the ascent of the lifeboat may be controlled and by which also the lifeboat may be returned to the submarine.

Another object of my invention is to provide means of communication between the lifeboat and the submarine while the latter is ascending or descending, or while it is at the surface of the water for observation purposes. Other important features of my invention relate to devices for adjusting the buoyancy of the lifeboat in correct proportion to the load; to improved devices for unwinding and rewinding the cables which connect the lifeboat to the submarine; to an improved arrangement for securing or releasing the lifeboat from the submarine, and to other arrangements and combinations of parts which will be hereinafter described and more particularly pointed out in the appended claims.

A preferred form of my invention is shown in the drawings in which—

Figure 1 is a plan view of a lifeboat with the upper covering or deck removed;

Fig. 2 is a sectional elevation taken along the line 2—2 in Fig. 1;

Fig. 3 is a diagrammatic view illustrating the manner in which the lifeboat is to be used;

Fig. 4 is an end elevation of the lifeboat with an adjacent portion of the submarine shown in section;

Fig. 5 is a plan view of one of the locking pins which secure the lifeboat in position on the submarine together with a portion of the mechanism for operating said pin;

Fig. 6 is an end elevation of the parts shown in Fig. 5, the frame of the lifeboat and of the submarine being shown in section;

Fig. 7 is a side elevation, partly in section, of the winding mechanism, including the drum to which is secured one of the cables which connect the lifeboat to the submarine, 60 and

Fig. 8 is a front elevation of the mechanism shown in Fig. 7.

As shown in Fig. 3 the submarine S is equipped with two lifeboats L and L' each of which has the general outline of a round-bottomed boat, and has a flat closed deck from which projects an observation structure 10. This structure is provided with windows or port-holes 11 and with a hinged 70 cover or hatch 12 through which entrance and exit is obtained.

Each lifeboat is normally received in a depression formed in the upper deck or frame 13 of the submarine, the walls of said depression corresponding in outline to the hull of the lifeboat. Around the edge of the depression a groove 15 (Fig. 6) is formed in the frame 13 of the submarine, and the inner edge of the frame is beveled as indicated at 16. The hull of the lifeboat is provided with a flange-like projection 17 shaped to correspond with the edge portion of the frame 13 above described. For this purpose the flange is provided with an inverted groove 18 and a beveled outer portion 19.

Any suitable soft packing material 20 may be placed in the grooves 15 and 18 to insure a tight joint between the lifeboat and the submarine, the grooved flange 17 extending entirely around the lifeboat. When the lifeboat and submarine are drawn tightly together by locking devices to be described a substantially water-tight joint is thus secured. These locking devices comprise locking pins by which the lifeboat is secured in position and mechanism by which these pins may be simultaneously withdrawn.

Referring to Figs. 5 and 6, each locking pin 25 is slidable in a bearing 26 secured to the frame 27 of the lifeboat, suitable packing 28 preventing the entrance of water around the pins. At their outer ends the pins 25 are provided with tapered portions 108 29, engaging corresponding openings or pockets 30 in the frame 13 of the submarine. At its inner end each pin 25 is threaded into a block 32 having rack teeth 33 formed on one edge thereof. The teeth 33 engage a pinion 34 fixed on a shaft 34 mounted in bearings 35 and 36 formed on a bracket 37

secured to the frame 27 of the lifeboat. A roll 38 is mounted on a stud 39 carried by the bearing portion 36 and holds the block 32 with its teeth 33 in engagement with the pinion 34. An actuating arm 40 is connected to the shaft 34 and at its free end is provided with an upwardly projecting stud 41.

The several studs 41 associated with the 10 different locking pins are connected to each other by links 42 (Fig. 1), and the whole system of links is preferably connected to suitable mechanism through which the entire series of locking pins may be simultaneously withdrawn. As shown in Fig. 1, the 15 link system on each side of the lifeboat is connected by a short link 43 to a cross-head 44 connected to the piston of a pneumatic cylinder 45. The air pressure in the cylinder is controlled by suitable valves and the 20 piston may be thus operated to lock or release the lifeboat by moving the locking pins 25.

A hand wheel 46 (Fig. 1) is mounted on 25 a sleeve 47 threaded upon the tail rod of the pneumatic piston. The hand wheel and sleeve normally move axially with the piston as the piston is operated, but, if desired, such axial movement of the hand wheel and sleeve 30 may be prevented by inserting pins 48 in a groove in the sleeve 47. The piston and links may then be moved manually by rotating the hand wheel 46.

A swinging hatch 50 (Fig. 4) closes the 35 opening from the submarine and a sliding valve 51 (Fig. 1) is provided for closing the corresponding opening in the bottom of the lifeboat. The valve 51 may be operated by a rack 52, pinion 53, and hand wheel 54, or it may be actuated by a piston 55 slidable 40 in a pneumatic cylinder 56, the air pressure therein being controlled by suitable valves. When the lifeboat has been securely seated and locked in the depression in the submarine, the small amount of water remaining 45 in the narrow space between the two boats may be removed by a pump 60 through a pipe 61. After the water is removed the hatch 50 and the valve 51 may be opened to 50 permit free passage from one boat to the other.

For the purpose of controlling the ascent or descent of the lifeboat I provide two cables 65-65 for each lifeboat, the lower 55 end of each cable being permanently secured to the submarine, and the other end of each cable being secured to the drum of a suitable winding mechanism or windlass. The construction of this winding mechanism is best shown in Figs. 7 and 8 in which it will be seen that each cable 65 is led through an opening 66 in the bottom of the lifeboat to a water-tight chamber or case 67 within which the winding drum 68 is 65 rotatably mounted. The drum is supported

in bearings 69 and 70 and each bearing is provided with a stuffing box 71 to prevent leakage of water through the bearing. Upon the left-hand end of the drum shaft, as shown in Fig. 7 there is secured a gear 72 70 meshing with a pinion 73 upon a transmission shaft 74 to which is secured a gear 75 meshing in turn with a second pinion 76 connected by a clutch 77 to a transmission shaft 78.

The shaft 78 extends longitudinally of the boat, preferably beneath the inner bottom of the boat, and is driven by suitable gearing from an electric motor 80 (Fig. 1). The winding mechanism at each end of the boat 80 is identical and by the clutches 77 either or both drums may be driven from the transmission shaft 78. The unwinding or rewinding of the cables may thus be accomplished by power and the winding drums 85 may be operated simultaneously or separately to retain the lifeboat upon an even keel.

A pinion 83 (Fig. 7) is mounted on a shaft 84 provided with a hand-wheel 85 and 90 slideable in bearings 86 and 87 supported on the casing 66. When in its full line position (Fig. 7) the pinion 83 engages the gear 72 for manually rotating the winding drum. When the drum is to be operated by power 95 the pinion may be moved to its dotted line position (Fig. 7) in which it does not engage the gear 72.

In order to establish telephone communication between the lifeboat and submarine 100 during its ascent or descent, or while it is at the surface for the purpose of observations, I provide an insulated wire 90 in the cable 65, said wire being connected through an axial passage 91 and an insulating strip 92 105 to an insulated ring 93 engaged by a brush 94. The brush 94 at one end of the cable may be connected to one side of a suitable telephone circuit in the lifeboat and the opposite end of the cable may be connected to a 110 similar circuit in the submarine. The other side of each circuit may be grounded or a complete metallic circuit may be obtained by using a second insulated wire 90 in the second cable 65.

The use of the lifeboat is clearly indicated in Fig. 3 in which the boat L is shown connected by its cables 65 to the submarine S while in a position for making observations at the surface of the water. The lifeboat L is shown disconnected from its cables, and moving to a more distant point.

I provide each lifeboat with a pair of floats 100 for attachment to the cables when it is desired to disconnect the lifeboat therefrom. These floats may be conveniently carried in recesses in the deck of the lifeboat. For securing the cables 65 to the floats 100 I provide a ring 101 loosely encircling each cable and connected by a rope or wire 102 to 130

a pin or ring 103 in the side of the lifeboat. When the lifeboat has reached the surface the rope 102 may be drawn up bringing with it a loop of the cable 65. At suitable 5 points in the cable I provide separable connections which permit the cable to be disconnected. The lower end may be secured to one of the floats 100, which is then thrown overboard, the other end of the cable being 10 temporarily secured to the ring 103 or in any other convenient manner. When both cables are thus released, the lifeboat is free to move to any desired point and upon its return to its original position the floats may 15 be picked up, the cables 65 connected, and the winding mechanism started to gradually submerge the lifeboat and return it to its original position in the deck of the submarine.

20 In order to proportion the buoyancy of the lifeboat to the load to be carried, I provide water storage tanks 110 and 111 suitably connected to the water pump 60, and also provided with suitable air valves 112. By 25 forcing water into or out of these tanks the buoyancy of the lifeboat may be readily adjusted. The water pump 60 is connected through suitable clutch mechanism to the motor 80, as is also the air pump 115 which 30 supplies the air pressure to the tank 116.

Having thus described my invention the many advantages to be derived from the use thereof will be apparent. It will also be evident that many changes and modifications 35 may be made therein by those skilled in the art without departing from the spirit and scope of my invention as set forth in the claims, and I do not wish to be otherwise limited to the details herein disclosed, but 40 what I claim is:—

1. The combination with a submarine and a lifeboat therefor, of means to detachably secure said boats together, said means comprising a plurality of pins mounted in said 45 lifeboat and adapted to enter corresponding pockets in said submarine, racks connected to said pins, pinions engaging said racks to move said pins axially, arms connected to said pinions, links connected to said arms, 50 and means to move said links simultaneously to withdraw said pins.

2. The combination with a submarine and a lifeboat therefor, of means to detachably

secure said boats together, said means comprising a plurality of pins mounted in said 55 lifeboat and adapted to enter corresponding pockets in said submarine, racks connected to said pins, pinions engaging said racks to move said pins longitudinally, arms connected to said pinions, links connected to 60 said arms and forming a link system, and a piston connected to said link system and operable by fluid pressure to simultaneously move said links, and withdraw said pins.

3. In combination, a submarine, a lifeboat therefor, and cables carried in water-tight casings in said lifeboat, said casings having external openings through which the outer 65 ends of said cables extend to said submarine, and means within said lifeboat for unwinding and rewinding said cables both separately and simultaneously.

4. In combination, a submarine, a lifeboat therefor, and cables carried in water-tight casings in said lifeboat, said casings having 75 external openings through which the outer ends of said cables extend to said submarine, floats carried by said lifeboat, means effective for use to draw portions of said cables to the deck of said lifeboat, and detachable connections in said cables whereby 80 the outer portion of each cable may be detached from said lifeboat and secured to one of said floats.

5. In combination, a submarine, a lifeboat therefor, detachable connections between said 85 submarine and lifeboat, means effective through said connections to draw said lifeboat downward to said submarine when the latter is submerged, and floats to support the 90 free ends of said connections when detached.

6. The combination with a submarine and a lifeboat therefor, of means to detachably secure said boats together, said means comprising a plurality of pins mounted in said 95 lifeboat and adapted to enter corresponding pockets in said submarine, links connected to move said pins and forming a link system, power-actuated devices for moving said link system, manual means for moving said link 100 system, and devices for rendering said manual means operative.

In testimony whereof I have hereunto affixed my signature.

ERNEST P. HOWE.
